LEROY C. DOANE, OF MERIDEN, CONNECTICUT, ASSIGNOR TO THE MILLER COMPANY, OF MERIDEN, CONNECTICUT, A CORPORATION OF CONNECTICUT

LIGHTING FIXTURE

Application filed December 9, 1925. Serial No. 74,309.

The present invention relates to lighting fixtures, and is more particularly directed toward lighting units having shades which are supported about a single lamp socket.

5 An object of the present invention is to provide a shade holder for lighting fixtures which is suitable for releasably supporting a shade or globe, and preferably wherein the shade, the holder and a socket cover may be 10 bodily moved relative to the socket without disengaging the shade from the holder.

Another object of the invention is to provide a shade holder which is made up out of a small number of simple sheet metal stampings suitably fastened together so that certain of them may be bodily moved with the shade without releasing the shade.

In certain types of enclosed lighting fixtures, it is desirable to be able to lift the glass 20 shade or globe so as to provide access to the interior of the glass unit for cleaning the same and to facilitate lamp renewals, and the present invention also contemplates a shade support which permits raising the shade as 25 well as the provision of a removable closure suitable for use in an opening in the bottom of the enclosed glass unit.

In the accompanying drawings, there is 30 shown for purposes of illustration, one of the many possible embodiments in which the present invention may take form, it being understood that the drawings are illustrative of the invention rather than limiting the same.

35 In these drawings:

Figure 1 is a vertical sectional view through a lighting unit embodying both the shade holding feature and the movable closure above referred to;

40 Figure 2 is an enlarged vertical sectional view showing the construction of the shade holder, the socket cover being raised;

Figure 3 is a sectional view along the line 3-3 of Figure 1; and

45 Figure 4 is a plan view of the closure, showing it removed from the enclosing unit.

The lighting fixture is supported from a conventional loop 10, which is threaded onto the upper end of a tubular stem 11. The lower end of this stem is threaded as shown at

12, and a bushing 13 is threaded onto it. This bushing supports a spider 14, which may be suitably attached by passing it over the reduced lower end portion of the bushing, and wedging this reduced portion, as indicated 55 at 15. This spider has a plurality of downwardly bent ears 16, which are disposed outside the upper end of a lamp socket 17, which may be attached to the spider in the usual manner, by means of screws 18 which pass through the spider and into the socket structure. Straps 19 are riveted to the ears 16, as indicated at 20, and these straps pass downwardly alongside the socket 17, and are spaced a short distance outside the socket. These 60 straps, of which there are preferably three, pass through holes 21 in a ring 22. This ring is riveted inside the skirt 23 of a socket cover 24, as indicated at 25, so that the ring and socket cover may be moved as a unit. The 70 upper part of the socket cover 24 is drawn inwardly and is provided with a hole 25, slightly larger in diameter than the outside of the bushing 13. The outside of this bushing is threaded as indicated at 26, and a knurled 75 threaded nut 27 is threaded down onto the bushing so as to hold the socket cover in place, as shown in Figure 1.

The lower ends of the straps 19 are bent outwardly, as indicated at 28, so as to pass 80 into the hole 29 in the upper end 30 of a glass shade or bowl G so as to support the same. As here shown, the bead 31 on the lower end of the socket cover is adapted to pass down about the outside of the upper 85 end of the shade.

In making up the shade holder above described, one may rivet two of the straps 19 onto the spider 14 and then pass these straps through the holes in the ring 22, after 90 which the other strap is passed through the hole in the ring and riveted to the spider. The bushing 13 and spider 14 may then be wedged together, and the socket cover placed in position and riveted to the ring 22. 95

When it is desired to attach a shade to the shade holder above described, it is merely necessary to unloosen the knurled nut 27, and raise the socket cover upwardly, as indicated in Figure 2. One may then pinch 100

the lower ends of the straps inwardly, as indicated in dotted lines in that figure, so as to permit the shade to pass by. The socket cover is then slid downwardly along the stem, being guided by the straps 19 in the holes 21, the bead 31 being brought against the upper side of the glass and clamped in place by turning the nut 27 onto the bushing 13. The lower ends of the straps 19 are prevented from moving inwardly by the ring 22. The projecting part of these straps is so stiff as to be substantially rigid.

When the shade holder is used in lamps of a type in which it is desired to bodily lift the glass bowl, it is merely necessary to loosen the nut 27 and raise the bowl. This will cause a socket cover to slide up along the straps, as before. As, however, the upper edge of the bowl will remain inside the skirt of the socket cover, and as there will be no tendency to spring the straps downwardly, there will be no separation of the bowl from the supporting straps. The socket cover will freely slide up and down as the shade is raised and lowered, as the spring fingers 19 will not at this time be pressed tightly against the walls of the holes 21 in the ring 22. The position of the globe and socket cover when raised is indicated in dot and dash lines in Figure 1.

The lower end of the globe G is open, as indicated at 40. A ring 41, which may be in the form of a sheet metal stamping, is of the proper size to fit outside the opening in the globe. This ring has an inwardly directed flange 42, offset as shown at 43, to provide a shelf 44 and supports a glass disc 45. The flange 42 carries a fixed finger 46 riveted to it, as indicated at 47, which finger is of the proper configuration to pass up over the glass, as indicated. A second finger 48, shaped somewhat similarly to the finger 46, is pivotally mounted on the flange 42 by a rivet 49. This figure 48 is part of a sheet metal stamping 50, which extends for some distance above the flange 42, and which has a finger grip 51, which passes out through a hole in the stamping 41, so that one may grasp the finger grip 51 and pull it outwardly, thereby moving the finger 48 inwardly, so as to release the closure member. The movement of the movable finger is limited by an upwardly bent prong 52 which engages with the wall of the stamping. The glass disk 45 is held in place by a number of clips 53, which are soldered to the flange 42.

It is obvious that the invention may be embodied in many forms and constructions within the scope of the claims and I wish it to be understood that the particular forms shown and described are but a few of the many forms. Various modifications and changes being possible, I do not otherwise in any way limit myself with respect thereto.

I claim:

1. The combination with an enclosing glass globe having an upper opening for a globe holder and a lower opening to permit access to the interior of the globe, of a globe holder having fixed globe supporting members carried inside the upper opening and along which the globe may move when raised, a ring engaging with the inside of the fixed members and movable with the globe, or independently of the globe, and a removable closure for the lower opening. 70

2. The combination with an enclosing glass globe having an upper opening for a globe holder and a lower opening to permit access to the interior of the globe, of a globe holder having fixed globe supporting members carried inside the upper opening and along which the globe may move when raised, a ring engaging with the inside of the fixed members and movable with the globe, or independently of the globe, and a removable closure for the lower opening, said closure including a sheet metal ring carrying cooperative fixed and movable fingers to releasably hold the ring in the lower opening and a glass disk. 80

3. The combination with an enclosing glass globe having an upper opening for a globe holder and a lower opening to permit access to the interior of the globe, of a globe holder having fixed globe supporting members carried inside the upper opening and along which the globe may move when raised, a ring engaging with the inside of the fixed members and movable with the globe, or independently of the globe, means to clamp the ring in the lower position to prevent raising either the ring or the globe, and a removable closure for the lower opening. 95

4. The combination with an enclosing glass globe having an upper opening for a globe holder and a lower opening to permit access to the interior of the globe, of a globe holder having fixed globe supporting members carried inside the upper opening and along which the globe may move when raised, a ring engaging with the inside of the fixed members and movable with the globe, or independently of the globe, means to clamp the ring in the lower position to prevent raising either the ring or the globe, and a removable closure for the lower opening, said closure including a sheet metal ring carrying cooperative fixed and movable fingers to releasably hold the ring in the lower opening and a glass disk. 100

5. In an enclosed lighting unit, a glass globe, a socket, a support for the socket, the socket being adapted to carry a lamp inside the globe, a globe support carried from the socket support and including downwardly extending fixedly mounted spring fingers passing inside an opening in the top of the globe, the globe being movable along those 115

125

130

fingers, and a movably mounted reinforcing ring inside the globe supporting fingers to permit withdrawal of the globe when the ring is raised.

5 6. In an enclosed lighting unit, a glass globe, a socket, a support for the socket, the socket being adapted to carry a lamp inside the globe, a globe support carried from the socket support and including downwardly extending fixedly mounted spring fingers passing inside an opening in the top of the globe, the globe being movable along these fingers, a movably mounted reinforcing ring inside the globe supporting fingers to permit withdrawal of the globe when the ring is raised, a socket cover attached to the ring and engageable with the top of the globe, and a nut cooperative with the socket support and socket cover for clamping the globe between 15 the socket cover and fixed fingers.

20 7. In an enclosed lighting unit, a glass globe, a socket, a support for the socket, the socket being adapted to carry a lamp inside the globe, a globe support carried from the 25 socket support and including downwardly extending fixedly mounted spring fingers passing inside an opening in the top of the globe, the globe being movable along these fingers, a movably mounted reinforcing ring inside 30 the globe supporting fingers to permit withdrawal of the globe when the ring is raised, a socket cover attached to the ring and engageable with the top of the globe, the ring having 35 apertures through which the fixed fingers pass for guiding the socket cover, and a nut cooperative with the socket support and socket cover for clamping the globe between the socket cover and fixed fingers.

40 8. In a shade holder, a socket, a socket cover, a ring carried inside the skirt of the socket cover and provided with vertical holes, a spider carried above the lamp socket, straps carried by the spider and projecting through the holes, the skirt of the socket cover and lower ends of the straps being shaped to hold a shade therebetween, and a clamping nut for forcing the socket cover downwardly.

45 9. In a shade holder, a socket, a plurality of straps fixedly connected at their upper ends with the socket and extending down alongside the socket, the lower ends of the straps being bent outwardly and adapted to engage underneath the open end of a shade, and a socket cover slidably carried outside the straps and carrying a ring which engages inside the straps when the socket cover is lowered to prevent bending them inwardly.

50 10. In a lighting fixture, a supporting rod, a plurality of shade-holding fingers supported from the rod and substantially parallel with its axis, a socket cover slidably mounted on the rod and disposed outside the fingers, and means carried by the socket cover for 55 holding the lower ends of the fingers against

inward movement when the socket cover is in its lower position.

60 11. In a lighting fixture, a tubular supporting member, a lamp socket mounted at the lower end of the supporting member, a spider 70 attached to the lower end of the supporting member, said spider having arms extending beyond the lamp socket, fingers riveted to the arms of the spider and extending downwardly alongside the socket, the lower ends of the fingers being outwardly bent to provide shade supporting fingers, a socket cover slidably mounted on the supporting member, the skirt of the socket cover, when lowered, being spaced above the lower bent ends of the fingers to accommodate a shade, and a plate carried inside the skirt of the socket holder and having apertures through which the fingers pass, the fingers being movable inwardly to release the shade when the socket cover 75 is raised.

Signed at Meriden, in the county of New Haven and State of Connecticut, this 5th day of Dec., 1925.
